UNITED STATES PATENT OFFICE.

ARCHIBALD F. REDDIE, OF PHILADELPHIA, PENNSYLVANIA, ASSIGNOR TO McCALLUM & McCALLUM, OF SAME PLACE.

DESIGN FOR CARPET.

SPECIFICATION forming part of Design No. 23,992, dated February 5, 1895.
Application filed January 8, 1895. Serial No. 534,263. Term of patent 3½ years.

To all whom it may concern:

Be it known that I, ARCHIBALD F. REDDIE, residing at Philadelphia, in the county of Philadelphia and State of Pennsylvania, have invented and produced a new and original Design for a Carpet or other Fabric, of which the following, taken in connection with the accompanying drawing, is a specification and description.

10 The design illustrated in the accompanying drawing may be wrought in Brussels, Wilton, velvet or other carpet in such colors as may be designed.

15 In the accompanying drawing a is the body, b the border, and a and b the carpet, and the drawing clearly shows the peculiar or distinctive appearance which, when imparted to the carpet or other fabric, constitutes my invention.

What I claim as my invention, and desire to secure by Letters Patent, is—20 1. In a design for a carpet, the body a, substantially as shown.

2. In a design for a carpet, the border b, substantially as shown.

25 3. The design for a carpet consisting of the body a, and border b, substantially as shown.

In testimony whereof I have hereunto signed my name.

ARCHIBALD F. REDDIE.

In presence of—

A. R. MATHEWS,
ARTHUR STEWART.
